UNITED STATES PATENT OFFICE

HENRY BARTELS, OF CHICAGO, ILLINOIS

COMBINED BED AND MANTLE

Application filed April 21, 1930. Serial No. 445,893.

This invention relates to improvements in combined bed and mantle, and one of the objects of the same is to provide a folding cabinet bed formed with a mantle and with a fire-place for a gas log or other heating apparatus, and which when folded and out of use the bed will be completely concealed and the structure will have the appearance of a mantle fireplace.

10 A further object is to provide improved means for supporting the mantle frame when the same is unfolded.

A further object is to provide an improved structure of this character in which the bed will not only be foldable upon itself to produce a compact structure necessitating a minimum amount of space, but the entire structure including the mantle will be foldable and unfoldable with respect to the wall 20 of the room in which it is located.

25 A further object is to provide in a structure of this character improved means for detachably securing the bed in position, thereby rendering it possible to detach the bed from the mantle structure and use the same separately therefrom when desired.

To the attainment of these ends and the accomplishment of other new and useful objects as will appear, the invention consists in 30 the features of novelty in substantially the construction, combination and arrangement of the several parts hereinafter more fully described and claimed and shown in the accompanying drawings illustrating this invention, and in which

Figure 1 is a vertical, longitudinal, sectional view of a bed and mantle of this character constructed in accordance with the principles of this invention.

40 Figure 2 is a vertical sectional view on a different scale of the structure folded and with parts omitted.

Figure 3 is a sectional view taken on line 3—3, Figure 2.

45 Figure 4 is a detail perspective view showing the guide for one end of the support and lever.

Figure 5 is a sectional view on the same scale as Figures 2 and 3 showing the mantle folded downwardly, with parts omitted, and

showing some of the parts in dotted lines in a different position.

Figure 6 is a detail view taken on line 6—6, Figure 7.

Figure 7 is a side elevation of the bed 55 structure detached and unfolded.

Figure 8 is a view showing one of the legs folded.

Figure 9 is a detail view showing the leg 60 unfolded.

Figure 10 is a detail perspective view of one end of the supporting arm.

Figure 11 is a detail perspective view of the track on which the supporting arm moves.

Referring more particularly to the drawings the numeral 15 designates generally a mantle structure having a shelf portion 16 separate therefrom, and 17 designates generally the wall of the room adjacent which the mantle is secured. 70

The mantle frame 15 is supported for folding movements upwardly and downwardly by means of suitable links 18, one end of which is pivotally connected as at 19 to a fixed support while the other end is pivotally connected as at 20 to a projection 21 mounted upon the mantle frame so that during the unfolding movement a portion of the lower end of the mantle frame will pass behind the baseboard 22. 75

Secured to the frame and to extend lengthwise thereof are arms 23 which preferably terminate at one end adjacent the top of the frame and are secured thereto as at 24. The other end of the arms projects beyond the bottom of the frame 15 as at 25 and is bifurcated as at 26 (see particularly Figure 10) and in such bifurcation is arranged an anti-friction roller 27. The roller 27 is adapted to engage and move upon a stationary track 28 which is preferably curved as shown and the upper end 29 thereof is reduced to form a projection which, when the frame 15 is in its lowermost position, with the roller 27 resting behind the portion 29 of the track, will extend into the bifurcation 26 and thereby hold the arm 23 in position. 80

Two of these arms are preferably provided, one on each side of the structure. 85

Pivotaly mounted upon a fixed support 30 100

is a lever 31, and the pivot 32 is preferably located adjacent the end 33 of the lever. This end of the lever, when the frame 15 is in its lowermost position engages under a stop 34. The body of the lever in advance of the pivot is deflected or offset as at 35 to provide a portion 36 which will engage and rest upon the arm 23. The end 37 of the lever is deflected or inclined with respect to the portion 36 and passes through a guide 38 which is secured to the frame 15 and also to the arm 23 (see particularly Figures 4 and 5) and the guide 38 is so located that when the frame 15 is in its lowered position as shown in Figure 5, the edge of the portion 37 of the lever 31 will engage the top of the guide and will cooperate with the stop 34 on the other end of the lever to serve as a support for the mantle frame 15, thereby producing a rigid structure.

One of these levers 31 is arranged on each side of the frame.

Carried also by the mantle frame 15 is a member 39 provided with an inclined slot 40 having an open entrance end 41 and the inclined portion of the slot 40 extends to a point in close proximity to the arm 23.

One of these members 39 with the slot 40 is arranged on each side of the mantle frame.

A member 42 is also arranged on each side of the mantle frame and is spaced in advance of the member 39. This member 42 is provided with an open slot 43, for a purpose to be set forth.

The mantle frame during its folding and unfolding movements may be counterbalanced in any suitable manner preferably by means of springs 44, any number of which may be provided on each side of the mantle frame. One end of the spring 44 is anchored preferably to the pivot 32 of the lever 31 and the other end is anchored as at 45 to the mantle frame.

When the mantle frame 15 is lowered from the position shown in Figure 2 to the position shown in Figure 5, the rollers 27 will move along the tracks 28 until they contact with the portion 29 of the tracks 28. At the same time the lever 33 will be moved about its pivot 32, causing the inclined end 37 to move through the guide 38 until the mantle frame has reached its lowermost position and at this time the end 33 of the levers will engage under the co-operating stops 34.

Associated with the mantle structure is a foldable bed structure comprising sections 46 and 47 connected by means of links 48, one end of the link 48 being pivotally connected as at 49 with the section 46 and the other end 60 of the link is pivotally connected as at 50 (see Figure 6) with the bed section 47.

Stops 51 and 52 may be provided respectively on the sections 46 and 47 to engage under the link 48 adjacent the pivot to limit the unfolding movement of the bed sections.

Projecting laterally from the links 48 are lugs 53 and projecting laterally from the end of the sections 46 are similar lugs 54.

The lugs 54 are adapted to enter and move within the guide slots 40 in the members 39 while the lugs 53 are adapted to enter and be seated within the slots 43 of the member 42.

The slot 40 is inclined and extends below the bottom of the slot 43.

The bed is connected to the mantle by inserting the lugs 50 into the slots 40 in the members 39 through the open ends 41 thereof and the lugs 53 are adapted to be seated in the slots 43 in the members 42, the open ends of the slots facilitating the free detachment of the bed from the mantle structure so that the bed may be used independent with respect thereto.

Springs 55, any number of which may be provided, are anchored at one end as at 56 to a fixed support and at their other end as at 57 to the end of the bed section 46, and serve as a means for counterbalancing the folding and unfolding movement of the bed sections and also operating to properly position the bed sections during such folding and unfolding movements, but are not under tension when the bed is unfolded.

When the bed sections are folded with respect to the mantle as shown in Figure 1 in the drawings, the lugs 54 on the sections 46 will be seated in the slots 40 in the members 39 adjacent the bottom of the slots and will therefore be lower than the lugs 53 seated in the bottom of the slots 43. The springs 55 will then be under tension.

When the bed sections are unfolded, by raising the section 47, turning the same about the pivot 49, the links 48 will also turn about the pivots 53 and this will cause a longitudinal movement to be exerted upon the section 46, which assisted by the stress of the springs 55 will cause the lugs 54 to rise in the slots 40 in the member 39 until the lugs 54 are in substantially the same horizontal plane as the lugs 53.

During the folding movement of the bed sections the movement of these parts will be reversed.

Suitable legs 58-59 are pivotally connected respectively as at 60 and 61 with the bed sections 47 and these legs are connected respectively by means of links 62-63 with the links 48 as at 64. One end of the link 63 is connected to one of the legs 58 while the free end of the link 62 is pivotally connected with the leg 59, and the legs on opposite sides of the bed are connected in any suitable manner to cause the respective legs 58 and 59 to move in unison.

With this construction it will be manifest that when the section 47 is moved about the pivot 50, and the links 48 moved about their pivots 53, the links 62 and 63 being connected

to the link 48 as at 64 will cause the legs 58 and 59 to swing about their pivots 60 and 61 to be folded or unfolded with respect to the bed section 47, and the free ends of the legs 5 will be moved inwardly so as to fold to the position shown in Figure 1.

The legs 59 are located at one end of the section 47 while the legs 58 are located at the other end of the section 47 and rest upon the 10 floor below the mantle frame structure when the latter is lowered.

The other end of the bed section 46 is supported by the lugs 54 and 53.

When the bed is to be detached from the 15 mantle structure it is only necessary to disengage one end of the springs 55 from their anchors, after which the bed may be bodily removed.

When removed, the free end of the section 20 46 is supported by suitable legs 65 which are pivotally connected as at 66 to the section 46. Links 67-68 are pivotally connected at one end as at 69. The other end of the link 67 is connected as at 70 with the bed section 46 25 and the other end of the link 68 is pivotally connected as at 71 with the legs 65, and these links knuckle with respect to each other when the legs are folded.

A portion of the legs 65 extend above the 30 section 46 when the legs are unfolded and the extending portion is cut away to form a lug or projection 72 that enters a slot 73 in an upwardly projecting portion 74 at the end of the bed section 46 and serves as a 35 means for assisting in holding the legs in proper position.

A headboard 75 may be fastened and connected to the projection 74 on the bed section 46 to fold with respect to the latter and a 40 footboard 76 is pivotally connected as at 77 to a similar projection 78 on the end of the bed section 47, and if desired any number of springs 79 may be provided for holding the footboard section 76 in folded or unfolded 45 position.

While the preferred form of the invention has been herein shown and described, it is to be understood that various changes may be made in the details of construction and in the 50 combination and arrangement of the several parts, within the scope of the claims, without departing from the spirit of this invention.

What is claimed as new is:-

55 1. A combined mantle and folding bed embodying a mantle adapted to swing upward and downward, links pivotally connected with the mantle and a fixed support and constituting pivots about which the mantle swings, arms connected with the mantle and projecting beyond the lower end of the mantle, anti-friction rollers at the ends of said arms, stationary guide tracks against which said rollers move, levers pivotally supported intermediate their ends upon fixed

fulcrums, guides connected to the mantle and movable therewith and through which guides one end of said levers pass, fixed stops to be engaged by the other end of said levers whereby the weight of said mantle and bed 70 structure will be supported by said levers when the mantle is unfolded, and a bed frame supported by the mantle and foldable with and with respect thereto.

2. A combined mantle and folding bed embodying a mantle adapted to swing upward and downward, links pivotally connected with the mantle and a fixed support and constituting pivots about which the mantle swings, arms connected with the mantle and projecting beyond the lower end of the mantle, anti-friction rollers at the ends of said arms, stationary guide tracks against which said rollers move, levers pivotally supported intermediate their ends upon fixed 75 fulcrums, guides connected to the mantle and movable therewith and through which guides one end of said levers pass, fixed stops to be engaged by the other end of said levers whereby the weight of said mantle and bed 80 structure will be supported by said levers when the mantle is unfolded, a bed frame supported by the mantle and foldable with and with respect thereto, and means connecting the bed structure with the mantle for 85 detachment therefrom as a unitary structure.

3. A combined mantle and folding bed embodying a mantle adapted to swing upward and downward, links pivotally connected with the mantle and a fixed support and constituting pivots about which the mantle swings, arms connecting with the mantle and projecting beyond the lower end of the mantle, anti-friction rollers at the ends of said arms, stationary guide tracks against 100 which said rollers move, levers pivotally supported intermediate their ends upon fixed fulcrums, guides connected to the mantle and movable therewith and through which guides one end of said levers pass, fixed stops to be 105 engaged by the other end of said levers whereby the weight of said mantle and bed structure will be supported by said levers when the mantle is unfolded, and a bed frame supported by the mantle and foldable 110 with and with respect thereto, the end of said levers which pass through said guides being inclined, a portion of the levers intermediate their ends engaging and resting upon said arms when the mantle is unfolded.

4. A combined mantle and folding bed embodying a mantle adapted to swing upward and downward, means constituting pivots about which the mantle swings, arms secured to the mantle and projecting beyond the 115 lower edge thereof, anti-friction rollers on said arms, fixed guides against which the rollers move for supporting and sustaining the weight of the mantle when upright and during its opening and closing movements, 120 125

levers pivotally mounted intermediate their ends upon fixed fulcrums, guides connected with the mantle and through which one end of the levers slide, and fixed stops to be engaged by the other end of the levers whereby the weight of the structure when unfolded will be supported by said levers.

5. A mantle adapted to fold upward and downward, a stationary base, with respect to 10 which the mantle is foldable, links pivotally connected to the mantle and a fixed support and constituting pivots about which the mantle swings, arms connected with the mantle and projecting beyond the lower end 15 of the mantle, said arms being bifurcated at one end, rollers in said bifurcations, and stationary guides against which the rollers move during the upward and downward folding movements of the mantle, one end of said 20 guides being reduced to extend over said rollers and enter the respective bifurcations when the rollers are in proximity thereto.

In testimony whereof I have signed my name to this specification, on this 12th day of 25 April, A. D. 1930.

HENRY BARTELS.
